DESIGN FOR A GOGGLE FRAME

Joseph C. Foster, Leominster, Mass., assignor to
Fosgood Corporation, Leominster, Mass., a
corporation of Massachusetts

Application August 12, 1939, Serial No. 86,634

Term of patent 3½ years

To all whom it may concern:

Be it known that I, Joseph C. Foster, a citizen of the United States and resident of Leominster, in the county of Worcester and State of Massachusetts, have invented a new, original, and ornamental Design for a Goggle Frame, of which the following is a specification, reference being had to the accompanying drawing, forming part thereof, in which:

Figure 1 is a perspective view of a goggle frame embodying the design; and
Fig. 2 is a front elevation thereof.

I claim:

The ornamental design for a goggle frame, substantially as shown.

JOSEPH C. FOSTER.
